TO WIRELESS SPECIALTY APPARATUS COMPANY, OF BOSTON, MASSACHUSETTS, A
CORPORATION OF NEW YORK.

THERMIONIC TUBE.

Application filed March 7, 1922. Serial No. 541,693.

This invention relates to thermionic tubes.

The object of the invention is to provide for such tubes an emitter of electrons which will permit the employment of alternating current for heating while at the same time prevent the varying potential of such current from deleteriously affecting the action of the elements of the tube.

The invention consists of an organization substantially as described herein, pointed out as to novelty in the claims, and shown in the accompanying drawings which are about four times scale, and of which

Figure 1 is a longitudinal section;

Fig. 2 is a like view of a modification;

Fig. 3 is a like view of another modification;

Fig. 4 a like view of yet another modification; and

Fig. 5 a diagrammatic illustration of a radio receiver set employing the invention in each of a plurality of tubes.

Heretofore tube filaments or emitters for receiving tubes have been heated by direct current as from storage batteries, this notwithstanding the desirability for convenience of employing alternating current, and on account of the disturbance or hum created by the potential across the legs of the filament if an alternating current be used. It is highly desirable to employ alternating current because it may be easily and cheaply transformed down to the proper voltage for the filament, and is nearly always available, as in practically all house-lighting circuits. The employment of storage batteries is much less desirable because they involve an initial expense constituting a large part of the total cost of radio-receiving apparatus; they must be frequently re-charged, necessitating either the use of an adjacent rectifier, or the transportation of the battery to a distant charging station; and this recharging becomes a greater inconvenience when an amplifier train of several tubes is used as in present-day practice, which makes a large demand upon the battery. Also the storage battery is a source of acid spray. But notwithstanding the disadvantages of the storage battery and the advantages of the alternating current, use of the battery with receiving tubes has continued up to the present time on account of the effect of the alternating difference of potential across the legs

of the filament when alternating current is employed. This varying potential creates a varying electrostatic field in the vicinity of the filament which induces a varying potential on the grid or control element of the tube, thereby varying the plate-filament current so as to cause a loud hum in the telephone receivers supplied by the tube. This action of the alternating current is probably somewhat complex, but may be assumed to be due in large part to the varying potential induced on the grid; secondarily, to the varying electrostatic field around the filament itself; and in some part also due to thermal variations of the filament, at least when a thin filament is used. While alternating current for heating the filament has been used in high power tubes for radio transmitter use (wherein the effect of the alternating fields around the filament is swamped by the high potentials employed on the grid and plate elements of the tube), yet in tubes employed for radio receiving purposes, the direct current as from storage batteries has been universally employed by reason of the above.

In accordance with this invention, the source of the emission of electrons for use in the operation of the tube is not the incandescent filament, as generally employed heretofore, although there is employed an electrical heater adapted for operation by an alternating current. Here the emitter of electrons consists of an element the surface of which is at substantially the same potential at all points and times. Also the emitting element may serve not only as a source of electrons but as a shield located between the heating element and the other elements of the tube such as the grid and plate.

In Fig. 1, the emitter for glass tube T is shown as comprising a thin platinum tube or thimble F, permissively about one-sixteenth of an inch or less in outside diameter and, say, about one-quarter or one-fifth of an inch long. In all the drawings, the emitter is shown in enlarged scale, and actually these parts will be made as small as possible in order to avoid the use of a large heater for the emitter, and in order to keep down the electrostatic capacity of the tube (i. e., the capacity between the grid and emitter and the capacity between the grid and plate), so that the tube may be used effec-

tively on short wave-lengths. As to the desired small size of the heater, it is to be noted that the heat dissipated at a given temperature is directly proportional to the area. An emitter of the above general dimensions may have an input of, say, 2.8 watts and an electron-emitting area of, say, 0.3 square centimeter.

The outside surface of emitter cylinder F is coated with lime or other suitable oxid, such as barium or strontium, in the manner now well known in the art (a V or hairpin filament has been used, coated with some such oxid, for the purpose of emitting electrons in abundance in a thermionic tube; but like the other filaments employed, this could not be used with alternating current for the reasons above stated).

Inside of tube F is a heater H, consisting of a fine wire hairpin or coil of suitable material which will stand the desired temperature without melting, i. e., such as nichrome, tungsten and the like. Surrounding heater H and filling the interior of tube F may be a suitable insulating filling I such as a high melting point enamel or mica. Insulator I may be air, or any substance which is a reasonably good conductor of heat, with a melting point sufficiently high to withstand a red heat, and a fair electrical insulator for low voltages. Also it should be of some substance, as stated, which will not interfere with the exhaustion of the thermionic tube or with the maintenance of the high vacuum during the life of the tube. (By "air", I mean the gaseous fluid, whatever it may be which is within the glass tube and which is maintained at a low pressure usually referred to as a more or less perfect "vacuum.") Crushed quartz may be used for this insulating filling I, packed or tamped into tube F so as to hold heater H securely in central position.

The grid element G and the plate element P may be arranged in any usual manner as shown, i. e., concentric with emitter F.

The entire emitter F, with its heater H, is supported on wires W of platinum or the like, which are thin to prevent thermal conduction away from the emitter. One of these supporting wires W is electrically connected by conductor X with an electrostatic shield S which surrounds the entrance leads A, A to heater H. (But shield S may be electrically connected with emitter F in any way which may be found convenient in the assembly of the thermionic tube.) This shield S extends up near to the lower edge of thimble F, but does not touch it, being there insulated from it. Shield S may be of any thin construction of metal such as nickel, suitably supported in relation to glass tube T, and, together with thimble emitter F, shield S forms an electrically-continuous surface all permissively at the same potential through-

out, and electrically completely shielding the space around emitter F from any flux from the alternating current supplied through leads A, A to heater H. Shield S should be an electrical conductor, as stated, of a kind which will not interfere with the exhaustion of the thermionic tube as by gases occluded or otherwise held. Shield S need not be employed when the thermionic tube and the electric heating leads are constructed and arranged so that the interior space does not surround the leads in the sense of causing resultant deleterious action from alternating currents through the leads.

The various leads from tube T may be taken out in any desired manner, as usual; the heating leads A, A being taken out through glass tube T as shown, from heater H, the lead G¹ from grid G, and the lead P¹ from plate P. The lead from emitter F (the outside circuit lead as distinguished from the heating wires A, A) may be W¹ as a continuation of one of the supporting wires W.

The heating wires A, A may be connected to any suitable source of alternating current of the proper potential, such as the secondary Z (Fig. 1) of an ordinary alternating current transformer, the primary of which, not shown, may be connected to the ordinary house-lighting mains, as at 60 cycles.

Emitting tube F may consist of platinum, alloyed with a small percentage of iridium (6%), and covered with the oxids of barium and strontium. These oxids may be applied alternately, and after each oxid application the temperature of the tube is momentarily raised to about 1,000° C. As many as sixteen such applications may be made, and after that the tube may be baked at about 1,200° C. for two hours. Heater H preferably may be so designed that when operated on the working alternating current voltage, there will be dissipated in the tube approximately eight watts per square centimeter of tube F area. The area of the tube F will, of course, depend upon the desired plate-current, and for ordinary detector and amplifier work this area may be generally between 0.2 and 0.5 square centimeter, so that the heater will be designed to dissipate between 1.6 and 4.0 watts.

Such a tube as the above is adapted for heating of the emitter by alternating current, for any purpose where the potentials of the plate and grid are not sufficiently high to swamp the alternating fields around the filament. For example, the tube of this invention may be used in radio communication receiving circuits as detector or amplifier (see Fig. 5), and it may be used as a relay in telephone lines, as thermionic tubes now are employed; and in all such cases the step-down alternating current transformer Z (Fig. 1) or any other convenient source of

alternating current may be substituted for the storage battery heretofore used with prior thermionic tubes, without any deleterious effect on the thermionic tube of this invention or its operation.

The invention may be embodied in various forms, but its embodiment requires nothing out of the usual practice in respect of the design or exhaustion of the glass or 10 other structure which may enclose the elements. Those skilled in the art of thermionic tubes may employ in combination any or all of the things advantageous for such tubes, in embodiments of the invention 15 which may be specifically different from any form shown herein.

The emitter F, in that it may consist of a metal base having the oxid coating, is to that extent like the Wehnelt cathode construction which heretofore has been employed in the form of V or hairpin filaments in thermionic tubes, where the oxid-coated filament was heated by direct current or from a storage battery; but the emitter herein 20 of may consist equivalently of any material or materials capable of emitting electrons freely when heated, high incandescence not being requisite in this class of thermionic emitters as in the case of uncoated filament 25 emitters.

In the modification of Fig. 2, heater H¹ (instead of being a hairpin filament insulated from emitter F), is a fine wire electrically connected to the upper end of emitter F whereby the latter acts as a return heating lead, thereby simplifying the construction. In Fig. 2 the emitter F is in the form of Fig. 1 with its exterior oxid layer FO. The cross section of this emitter F 40 is so proportioned relative to that of its heater H¹ that the voltage drop along the emitter will be little, if any, and substantially negligible in its effect on the action of the tube, in any case. This proportioning will result substantially without special design, when heater H¹ consists of a fine wire having a cross section from say ten to one hundred times smaller than that of emitter F; but this proportioning is important and 45 should be taken into consideration in the design of emitter and heater. In this form (and in other forms as shown in Fig. 3), no insulating substance need be used in the space between the heating portion H¹ and the emitter portion F; so that the heat is transferred to emitter F partly by radiation across the short vacuous space between the heating and emitting parts, and partly by conduction via the contact between the two. Most of the 50 heat transfer may be caused to be effected, if desired, by the latter means. Also in the form of this Fig. 2, the left-hand heater lead HL will be identical with lead FL from the emitter. A nickel shield S (as in Fig. 55 1) serves to shield the space within ther-

mionic tube T around the heater leads HL, HL from any electrostatic field from said leads; and conductor X connects shield S to lead FL. The grid coil G, cylindrical plate P and their respective leads GL and 70 PL are made and brought out in the usual manner, and in Fig. 2, as stated above, one of the heater-leads HL is also the emitter-lead FL to the tube-circuit.

In Fig. 3 emitter F² (having oxid coating 75 FO) is in the form of a flat circular disk of platinum F (cf. Fig. 1), about one-quarter inch in diameter or less, and say two or three thousandths of an inch thick. This disk F is supported on a central rigid stalk 80 FL², forming a part of the lead from the emitter to the circuit of the tube.

Underneath disk F² is the heater H², H², consisting of tungsten or other wire of high melting point. Heater H² and disk F² may 85 contact at their midpoints, as shown. The heater may be supplied with alternating current by leads HL², HL². This heater heats the disk F² partly by radiation and partly 90 by conduction at the point of contact or attachment. The most effective form probably is one wherein a thin layer of enamel thermally connects the coil of resistance wire H² to emitter F², pursuant to conventional 95 rheostat practice; thereby the enamel layer 100 serves to support the resistance wire close to the emitter to be heated, electrically insulates it therefrom, and as a thin layer constitutes a sufficiently good thermal conductor to permit the effective transfer of 105 heat.

Above disk F² the grid G² is held in position by the stiff grid-lead GL²; grid G² consisting of a flat spiral of fine wire. Above grid G² the plate element P² is supported 110 on the plate-lead PL² and also, if desired, by a separate support PS. A nickel shield S² electrically shields the interior of the tube from heater leads HL, HL and is electrically connected by conductor X² to emitter disk F². By the above construction and arrangement of emitter and heater, the emitter itself will have little, if any, voltage drop along it.

In the modification of Fig. 4, the heater wire H³ is embedded in a tubular insulator I³ (cf. Fig. 1), which may be a short piece of fused quartz tubing. Heater leads HL³, HL³ enter the tube from opposite ends. On the surface of insulator I³, a thin platinum tube F³ is spun or deposited. On the outer surface of this emitter tube F³ is the suitable emitting coating FO² (cf. Fig. 1). Nickel (or other) shield tubes S³ are supported from opposite ends of thermionic tube T³ to enclose the respective heater leads HL³, HL³. These shields S³ are slipped over the ends of tubular insulator I³ to overlap them, and approximate but 125 do not touch emitter tube F³. Shields S³ 130

are electrically connected to emitter F^3 by fine wires X^3 , X^3 , this arrangement preventing excessive loss of heat by a thermal connection of large cross-section. Grid G^3 and its lead GL^3 , and plate P^3 and its lead PL^3 are as in Figs. 1 and 2. Emitter lead FL^3 to the external tube circuit is taken from one of the two shields S^3 .

In any case, the thermionic tube may be 10 constructed so that the emitter may be heated by current from a storage battery alternatively with alternating currents, if and whenever convenient or desired.

Fig. 5 illustrates an ordinary radio receiving set employing two thermionic tubes, each of which embodies the invention. Here, the signals are received by antenna A, passed by transformer OT to the first thermionic tube T^1 acting (at left) as detector, and then passed by the usual transformer AF to the second thermionic tube T^2 acting (at right) as amplifier, whence the amplified currents pass to the telephone receiver shown. The current for heating 25 the heaters for the emitters F^1 , F^2 of the two tubes is furnished from a step-down transformer T supplied from an ordinary sixty-cycle main to the heater leads A, A. The plate element P of the first or detector 30 tube T^1 is connected via lead PL through transformer AF to the positive terminal of the plate battery PB (which may be a simple dry cell or cells), the negative pole of this battery being connected to emitter F^1 of 35 the first or detector tube T^1 via lead W^1 . In the two tubes here shown, each emitter, including its heater, is indicated as being constructed, for example, like the corresponding parts in Fig. 1. The second or right-hand tube T^2 , being the amplifier tube, has its grid G^1 connected via lead GL to one terminal of the secondary of transformer AF, the other terminal of AF being connected to the negative terminal of battery PB. The plate P^1 of the second tube 40 is connected to the receiving telephones and through them to the positive terminal of plate battery PB. The operation of this system of Fig. 5 is identical with that of the ordinary detector-amplifier train of tubes, with the exception of the emitter construction which permits the use of alternating 45 current for heating.

The forms of Figs. 2-4 may be constructed according to the preferred electrical and thermal proportions above described for the form of Fig. 1, especially as to emitter F.

I claim:—

1. In an electrically heated electron emitter for low power thermionic tubes of the evacuated glass-enclosed type having grid and plate electrodes independent of the emitter, the improvement comprising a small emitter member having an external emitting surface and an internal electric

heater, the emission surface constituting a shield between the heater and the grid of the thermionic tube; electric insulating material between the internal heater and the external emitting surface and supporting the emitting surface upon the heater; and circuit leads from the heater and extending through the glass tube; said emitting surface and electric heater being thermally isolated within the tube save for said circuit leads. 70

2. In an electrically heated electron emitter for low power thermionic tubes of the evacuated glass-enclosed type having grid and plate electrodes independent of the emitter, the improvement comprising a small emitter member having an external electron-emitting surface and an internal electric heating means; electric insulating material between the internal heating means and the emitting surface and supporting the emitter upon the heating means; and circuit leads for the heating means extending through the glass tube; said heating means and emitter being wholly supported by said circuit leads and thermally isolated within the tube save for such leads, the latter being substantially thin to prevent excessive thermal conduction. 80

3. In a low power thermionic tube of the evacuated glass-enclosed type having grid and plate electrodes independent of the emitter, the improved emitting means which comprises a small emitter member having an external emitting surface and an internal electric heating means, said external surface constituting an electrode shield between the grid and the heater; circuit leads for the electric heater; and a shield of metal located between the grid and portions of said leads extending outside beyond the emitter; said metal shield being connected by an electric lead to the emitting member but otherwise metallically independent thereof. 90

4. In a low power thermionic tube of the evacuated glass-enclosed type having three independent electrodes including grid, plate and electron-emitter, the improved emitter which comprises a small emitter member having an external emitting surface and a neighboring electric heater, said emission surface constituting a shield between the heater and the grid; circuit leads for the heater; a shield of metal located between the grid and parts of said leads which extend beyond the emitter member; and electric insulating material between the internal heating means and the emitter member and supporting the latter; the emitter member and the electric heater being thermally isolated within the glass tube save for said circuit leads. 100

5. In a low power thermionic tube of the evacuated glass-enclosed type having three 110

- independent electrodes including grid, plate and electron-emitter, the improved emitter which comprises a small emitter member having an electron-emission surface, and a 5 neighboring electric heater therefor, said emitter member constituting a shield between the electric heater and the grid; circuit leads for the heater and extending through and supported in the glass of the 10 tube; a shield of metal located between the grid and parts of said leads which extend beyond the emitter member; and electric insulating material between the emitter member and the electric heater and supporting 15 the emitter member on the heater; said metal shield being connected by an electric lead to said emitter member but otherwise metallically independent thereof.
6. In a low power thermionic tube of the 20 evacuated glass-enclosed type having three independent electrodes including grid, plate and electron-emitter, the improved emitter which comprises a small emitter member having an electron-emitting surface and a 25 neighboring electric heater, said emitter member constituting a shield between the electric heater and the grid; circuit leads for the heating means and extending through and supported in the glass of the tube; a 30 shield of metal located between the grid and parts of said leads which extend beyond the emitter member, said metal shield being
- connected by an electric lead to said emitter member but otherwise metallically independent thereof; and said emitter member and electric heater being supported inside the glass tube by said circuit leads alone independent of said metal shield. 35
7. In a low power thermionic tube of the 40 evacuated glass-enclosed type having three independent electrodes including grid, plate and electron-emitter, the improved construction and arrangement of emitter which comprises a small emitter member having an electron-emitting surface and a neighboring 45 electric heater, said emitter member constituting a shield between the grid and the heater; circuit leads for the heater and extending through and supported in the glass 50 of the tube; a shield of metal supported on the glass tube and located between the grid and parts of said leads which extend beyond the emitter member; and electric insulating material located between the emitter member and the heater and supporting 55 the emitter member on the heater; said metal shield being connected by an electric lead to said emitter member but otherwise metallically independent thereof; and said 60 emitter member and heater being supported inside the glass tube by said circuit leads independently of said metal shield.

GREENLEAF WHITTIER PICKARD.
